(57) **CLAIM**

The ornamental design for a capillary cartridge for electrophoresis, as shown and described.

DESCRIPTION

FIG. 1 is a front, top, and left side perspective view of a capillary cartridge for electrophoresis according to the design;

FIG. 2 is a rear, bottom, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a cross-sectional view taken along line 9-9 of FIG. 3.

The broken lines illustrate portions of the capillary cartridge for electrophoresis that form no part of the claimed design.

1 Claim, 7 Drawing Sheets
